CASSETTE

Halsey L. Raffman, Bronx, N. Y.

Application November 15, 1941, Serial No. 419,259

5 Claims. (Cl. 250—68)

This invention relates to cassettes.

An object of this invention is to provide a strong, compact and durable cassette, which shall be relatively inexpensive to manufacture, easy to assemble, and in which the composition plate may be readily replaced, and which shall be relatively easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a top plan view of a cassette embodying the invention, with parts broken away and in cross-section;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1;

Fig. 5 is an enlarged, cross-sectional view taken on line 5—5 of Fig. 1;

Fig. 6 is an enlarged, detailed view similar to one end of Fig. 3; and

Fig. 7 is a partial, top plan view of the cassette with the clamping cover plate opened up, and with parts broken away and in cross-section.

Referring now in detail to the drawings, 10 designates a cassette embodying the invention. The same comprises a rectangular frame 11 supporting a composition plate 12, and provided with a cover 13, adapted to be clamped to the frame to press negatives 14 against the composition plate.

The frame 11 is constructed of generally tubular sheet metal. Said frame has a front end 17, a rear end 18, and parallel side portions 19. Each of the front, rear and side portions has an outer vertical wall 20, and a horizontal flange 21 extending inwardly from the lower ends of the wall portions 20, and top horizontal wall portions 22 extending inwardly from the upper ends of said vertical wall portions 20.

It will be noted that the flanges 21 extend inwardly beyond the top walls 22, the composition plate 12 resting on the inner portions of flanges 21, as clearly illustrated in the drawings. Ex-

tending downwardly from the top walls 22 are vertical walls 24, the lower edges of which contact the flanges 21.

It will now be understood that the frame 11 comprises hollow tubular construction at the top, bottom and ends, with an inwardly extending flange to be engaged by the edges of the composition plate 12.

Means is provided to retain the composition plate 12 in flanges 21. To this end, there is attached to the vertical walls 24 of the bottom and top portions 17 and 18, straight bars 30 and 31. Bar 30 is attached to the front portion 17 by screws 30a, and bar 31 is attached to the portion 18 by screws 31a.

It will be noted that the bars 30, 31 are of rectangular cross-section, and are spaced above the flanges 21 a distance substantially equal to the composition plate 12. Furthermore the bars 30, 31 terminate short of the side portions 19 of the frame 11.

The ends of the wall portions 24, at the top and bottom of the frame are formed with openings 33 and 34, respectively. Attached to the inner surfaces of the vertical wall portions 24 at the sides 19 of the frame, are bars 35 attached to said wall portions 24 by screws 35a. The ends of bars 35 project through the openings 33 and 34, respectively, thereby affording rigidity to the frame construction. The ends of bars 30 contact the bars 35. The bars 35 are likewise of rectangular cross-section, and spaced above flanges 21 by a distance equivalent to the thickness of the composition plate, 12.

Composition plate is removable and replaceable by unscrewing screws 30a and 31a to permit removal of bars 30, 31 and by then removing screws 35a to permit bars 35 to be shifted endwise and then removed from the frame.

The clamping cover 13 comprises a cover plate 40, preferably smooth on its under-surface. The upper surface of cover plate 40 may be corrugated, as shown in the drawings. Attached to the under-surface of cover plate 40, is a pad or sheet 41 of felt and lead, or any other soft material, preferably folded around the edges of the cover plate, as at 42. Plate 40 is formed with two pairs of horizontally aligned projections or raised portions 43, for the purpose hereinafter appearing. The cover plate 40 is of such size as to fit within the bars 30, 31, 35 and it is adapted to press the negatives 14 against the composition plate.

Means is provided to hinge the cover plate 40 to the frame. To this end, there is fixed to the

upper end of said cover plate, a pair of hinged plates 45 having upwardly, offset portions 46 extending beyond the cover plate, said portions 46 being formed with ears 47, for the purpose hereinafter appearing.

The top wall 22 of top portion 18 of the frame is cut-away, as at 48, to admit portions 46 of the hinge plate 45. Wall 24 of frame portion 18 is likewise cut-away as at 49, to admit offset portions 46 of the hinge plate 45. Wall 24 of the rear portion 18 is further cut-away, as at 50, below the cut-away portions 49, sufficiently to admit the ears 47. The cut-away portions 50 are further covered by the bar 31 fixed to frame portion 18. Fixed to said bar 31 are a pair of rearwardly extending horizontal pins 53.

It will now be understood that upon removal of bar 31, portions 36, 47 of the hinges 45 may be inserted through the cut-out portions 50. The ears 47 are then raised to engage the wall 24 on opposite sides of cut-out 49. Bar 31 may then be attached in place so that the hinges cannot be removed from tubular portion 18. Pins 53 contact the outer edges of the hinge plates as the cover is swung upwardly.

It will now be understood that the hinge provides for up and down movement of the cover plate to accommodate different thicknesses inserted between the cover plate and the composition plate 12.

Means is provided to clamp the cover plate to the frame. To this end, there is attached to the cover plate a pair of upwardly extending rivet pins 60. Pivoted on each pin 60 is a spring clamp 61, each having a pair of outwardly extending arms 62. The walls 24 of side portions 19 of the frame are formed with longitudinal slots 64 to receive the outer ends of arm 62. The slots 64 on one portion 19 are offset with respect to said slots in the other portion 19, so that clamping member 61 may be rotated in one direction only, to clamp the cover plate, and in an opposite direction only, to release the cover plate.

It will be noted that the arms 62 engage the raised portions or projections 43 on the cover plate to press the outer ends of said arms against the upper edges formed by the slot 64 to clamp the cover plate to the frame. The arms 62 may be formed with recesses 68 adjacent their outer ends to receive the fingers of the operator to facilitate swinging of the clamp 61. The cover plate furthermore may be provided with a hinged loop 70 to facilitate lifting of the cover plate after it is released.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A cassette comprising a frame having at one end, an outer vertical wall, a horizontal top wall, and an inner vertical wall, said top wall having a cut-away portion, said inner vertical wall being cut-away adjacent its upper end to an extent equivalent to the cut-away at the top wall, and being cut-away adjacent its bottom end on opposite sides of the cut-away at its upper end, a bar fixed

to said inner vertical wall and covering the wider cut-away portion of said inner vertical wall, a cover for said cassette, and a hinged plate fixed to said cover and extending therebeyond, and formed with recesses, said hinge plate passing through the cut-away portion at the upper end of the inner vertical wall.

2. A cassette comprising a frame having at one end, an outer vertical wall, a horizontal top wall, and an inner vertical wall, said top wall having a cut-away portion, said inner vertical wall being cut-away adjacent its upper end to an extent equivalent to the cut-away at the top wall, and being cut-away adjacent its bottom end on opposite sides of the cut-away at its upper end, a bar fixed to said inner vertical wall and covering the wider cut-away portion of said inner vertical wall, a cover for said cassette, a hinge plate fixed to said cover, and extending therebeyond, and formed with recesses, said hinge plate passing through the cut-away portion at the upper end of the inner vertical wall, and means on said bar extending toward the outer vertical wall adapted to contact the outer end of said hinge plate.

25 3. A cassette comprising a frame having at one end, an outer vertical wall, a horizontal top wall, and an inner vertical wall, said top wall having a cut-away portion, said inner vertical wall being cut-away adjacent its upper end to an extent
30 equivalent to the cut-away at the top wall, and being cut-away adjacent its bottom end on opposite sides of the cut-away at its upper end, a bar fixed to said inner vertical wall and covering the wider cut-away portion of said inner vertical wall,
35 a cover for said cassette, a hinge plate fixed to said cover, and extending therebeyond, and formed with recesses, said hinge plate passing through the cut-away portion at the upper end of the inner vertical wall, and means on said bar
40 extending toward the outer vertical wall adapted to contact the outer end of said hinge plate, said frame having side portions likewise formed with outer vertical walls, horizontal top walls and vertical inner walls, the vertical inner walls of the
45 side portions of the frame being formed with longitudinal slots, and spring clamps pivoted to said cover plate, and having outwardly extending arms adapted to be received within said longitudinal slots.

50 4. A cassette comprising a frame having at one end, an outer vertical wall, a horizontal top wall, and an inner vertical wall, said top wall having a cut-away portion, said inner vertical wall being cut-away adjacent its upper end to an extent
55 equivalent to the cut-away at the top wall, and being cut-away adjacent its bottom end on opposite sides of the cut-away at its upper end, a bar fixed to said inner vertical wall and covering the wider cut-away portion of said inner vertical wall,
60 a cover for said cassette, a hinge plate fixed to said cover, and extending therebeyond, and formed with recesses, said hinge plate passing through the cut-away portion at the upper end of the inner vertical wall, means on said bar extending toward the outer vertical wall adapted to contact the outer end of said hinge plate, said frame having side portions likewise formed with outer vertical walls, horizontal top walls and vertical inner walls, the vertical inner walls of the
65 side portions of the frame being formed with longitudinal slots, and spring clamps pivoted to said cover plate, and having outwardly extending arms adapted to be received within said longitudinal slots, said cover plate having upwardly extending projections adapted to engage said
70
75

spring arms, when the spring arms are moved into said longitudinal slots.

5. A cassette comprising a frame having top, bottom and side portions, each of said portions comprising outer vertical walls, horizontal, inwardly extending top walls, and downwardly extending, inner vertical walls, and inwardly extending, horizontal flanges extending inwardly beyond said inner vertical walls, a composition plate mounted on said flanges, a pair of bars fixed to the inner vertical walls of the top and bottom portions of said frame, said inner vertical walls of the top and bottom portions of the frame being formed with openings at their outer ends, and a pair of bars fixed to the inner vertical walls of the side portions of the frame and having the ends thereof received within the open-

ings of the inner vertical walls at the top and bottom of the frame, the bar fixed to the inner vertical wall of the top portion of the frame, being provided with a pair of horizontal pins 5 extending toward the outer vertical wall of said top portion of the frame, a cover plate, hinge members fixed to said cover plate, the inner vertical wall at the top portion of the frame being formed with cut-outs widened at their lower ends, 10 and said hinge members having ears adapted to pass through the widened portions of the cut-outs, and the bar which is fixed to the inner vertical wall of the top portion of the frame, being adapted to cover the widened portions of 15 said cut-out.

HALSEY L. RAFFMAN.
